FLUID-PRESSURE SOLE PRESS

Harold E. Marasco, Swampscott, Mass.

Application February 6, 1956, Serial No. 563,549

7 Claims. (Cl. 12—36.8)

This invention comprises a new and improved sole press constructed and arranged for conforming and attaching soles to the bottoms of lasted shoes and operated by fluid pressure. It is herein shown as embodied in a press of the turret type such as that shown in my prior United States Letters Patent No. 2,608,703, September 2, 1952, and in one aspect constitutes an improvement of that machine although not by any means limited in its application thereto.

One object of the invention is to quicken the pressure applying step of the sole laying operation by simultaneously moving both the pad and the heel post under fluid pressure instead of moving only the pad as in the machine of my prior patent.

Another object is to improve the clearance conditions of the machine parts and so facilitate the step of presenting a lasted shoe to the pad box. This is effected by now locating the heel post at the beginning of each cycle at the point of maximum separation from the pad and then advancing the heel post simultaneously with the inflation of the pad.

An advantage of my novel construction is that it adapts the press for handling high and low heel shoes without interruption for the necessity of mechanical adjustment of the heel post as by ratchet mechanism or the like. It also obviates the danger of subjecting a lasted shoe to the sole laying operation with defective results while the heel post is improperly adjusted. The construction herein disclosed in general results in improving the speed and accuracy of the sole laying operation and for this reason it has been found that uniform and satisfactory results may be achieved with the employment of less pressure than heretofore.

These and other features of the invention will be best understood and appreciated from the following description of a preferred embodiment thereof selected for purposes of illustration and shown in the accompanying drawing in which the figure is a view in elevation with certain parts shown in longitudinal section.

The invention is herein shown as embodied in the machine of my prior patent above identified and certain details of construction, such as the starting and stopping mechanism, the valve and valve operating mechanism, while not shown herein may be identical or similar to the corresponding parts shown in the patent.

The frame 10 of the machine is designed to support a rotatable turret in which is included a fluid pressure reservoir in the shape of a vertically disposed cylinder 11 supported by ball bearings upon the frame. Fluid under pressure is supplied to the cylinder 11 and maintained always under working pressure through connections leading to the bottom of the cylinder. A cap or sleeve 13 is adjustably mounted on the upper end of the cylinder being held against rotary movement thereon by slot and pin connections and vertically adjusted thereon by means of a screw having a hand wheel 14.

The turret carries four to six sole press units of which two are shown in the figure. Arms 15 project radially

2

from the cylinder 11 and each carries at its outer end a base plate 16 inclined downwardly and outwardly at substantially 45°. Upon each of the base plates 16 is mounted a pad box 17 connected to the base plate for radial adjustment by a screw 18. The pad box contains an inflatable pad 19 of the usual well-known construction. Each pad is connected to the fluid pressure cylinder 11 by a radial pipe 20 in which is placed a valve 21. The valve may be opened manually with the press unit in its initial position or as it moves out of initial position, maintained open for a period and then may be closed as the unit completes its circuit in the rotation of the turret.

The adjustable cap or sleeve 13 is provided with outwardly extending overhanging arms 22 corresponding to the arms 15 of the cylinder 11. At the end of each arm 22 is a bracket 23 to which is secured a fluid pressure cylinder 24. A fluid pressure pipe 25 leads from the head of the cylinder 24 to the fluid pressure pipe 20 at a point adjacent the valve 21 and thus provides direct pipe connections between the cylinder and pad. From this it will be seen that the valve 21 controls the admission of fluid under pressure simultaneously to the pad 19 and the cylinder 24.

Within the cylinder 24 is provided a piston 26 connected to a piston rod 27 which carries the heel post 28. A coil spring 29 tends always to move the piston 26 to an initial position in the outer end of the cylinder 24, thus holding the heel post at its point of maximum separation from the pad 19.

Each arm 22 is also provided with a bracket 30 upon which is mounted a toe post 31 arranged to engage the forepart of the shoe in the sole laying operation.

In the figure the pad 19 is shown in collapsed condition and the heel post 28 in its initial position at the left side of the figure. It will be apparent that in this position maximum clearance of the parts is provided for presentation of a lasted shoe to the pad with a sole properly spotted on the shoe bottom.

Having thus presented the shoe under favorable clearance conditions, the valve 21 is opened either manually or automatically whereupon the pad 19 is immediately inflated and the shoe moved upwardly and outwardly thereby and simultaneously the heel post is advanced into the position shown at the right side of the figure. Full fluid pressure is thus rendered effective to carry out the sole laying operation and pressure is continued during the time interval of the turret rotation. In this rotation each unit is carried from the station of presentation to the discharge station and this may be spaced as much as 300° from the former. At the discharge station the valve 21 is operated to vent the pressure system of each unit to the atmosphere, whereupon the pad 19 immediately collapses and the heel post is retracted by the spring 29 to its initial position.

Having thus disclosed my invention and described in detail a preferred embodiment thereof, I claim as new and desire to secure by Letters Patent:

1. A sole press including in its structure an inflatable pad mounted to underlie the bottom of a lasted shoe, a fluid operated heel post mounted opposite the heel end of the pad, means for simultaneously inflating the pad and actuating the heel post by fluid under pressure, and means for simultaneously moving the pad and heel post in fixed relation.

2. A sole press including in its structure an inflatable pad mounted in outwardly inclined position to underlie the bottom of a lasted shoe as presented to the press, an overhanging arm carrying a fluid pressure cylinder that is located opposite to and above the heel end of the pad, a heel post and piston operatively associated with said cylinder, direct pipe connections between the pad and cylinder for admitting fluid under pressure to the pad and

to the cylinder, and means for bodily moving the pad and heel post as a unit.

3. A sole press including in its structure a rotatable turret, an inflatable pad mounted on the turret to underlie a lasted shoe, an oppositely disposed movably mounted heel post also mounted on the turret, and means carried by the turret for inflating the pad and advancing the heel post under the actuation of equal fluid pressure.

4. A sole press including in its structure a rotatable turret, a plurality of sole pressing units carried by the turret each comprising an inflatable pad, an overhanging arm, a fluid-pressure cylinder mounted on the arm, a piston in the cylinder carrying a heel post, and direct pipe connections between the pad and cylinder for conducting fluid under pressure to the pad and the cylinder while in rotation with the turret.

5. A sole press having a main frame and including in its structure a cylindrical fluid-pressure reservoir mounted in the frame for rotation about a vertical axis, a plurality of units spaced radially about said reservoir and each comprising an inflatable pad, an overhanging arm, a cylinder and piston carried by the arm, a heel post actuated thereby, and fluid pressure connections between said

reservoir on the one hand and said pad and cylinder on the other hand.

6. A sole press as described in claim 5 further characterized in that the fluid pressure connections are rotatable with each of the units and include a controlling valve for each unit.

7. In a turret sole press, an inflatable pad for underly 10 ing a lasted shoe, an overhanging arm carrying a fluid pressure cylinder and piston, a heel post mounted in the piston, a spring acting on the piston tending always to maintain it with the heel post in position of maximum separation from the pad, and connections for admitting fluid under pressure simultaneously to the pad and the fluid pressure cylinder.
